UNITED STATES PATENT OFFICE.

JOHN JAMES CANNON, OF LEICESTER, ENGLAND.

YARN-WINDING MACHINE.

Application filed March 10, 1922. Serial No. 542,611.

To all whom it may concern:

Be it known that I, JOHN JAMES CANNON, a subject of the King of Great Britain, residing at Leicester, in the county of Leicestershire, England, have invented new and useful Improvements in or Relating to Yarn-Winding Machines, of which the following is a specification.

This invention relates to yarn-winding machines and concerns those of the vertical spindle type wherein the yarn is built up on bobbins in a series of cones.

In machines of this class the yarn guide has imparted to it a vertical traverse and as the cones are built up one upon another, the guide is correspondingly moved to a higher position.

The guide works up a screwed rod mounted upon a bar to which an up and down motion is imparted, and it has long been the practice to obtain the upward movement of the yarn guide by means of a disc or feed cup rotatable on the screwed rod and having a milled periphery which, by contact with the wound yarn, has caused the disc to rotate and adjust its position in an upward direction on the rod.

The proper feeding i. e. upward movement, of the yarn guide on the screwed rod is dependent upon the frictional contact between the disc and the wound yarn, and as the quality and tightness of the latter varies, the actuation of the disc is not by any means constant or regular and on this account the yarn is not always built up with that degree of regularity which is desirable.

To overcome this difficulty mechanical means have been adopted for positively raising the yarn guide in conjunction with the traverse, and a stop motion has been arranged to automatically stop said mechanical means upon the yarn breaking, or the bobbin being stopped.

The present invention has reference to means of this character wherein the nut device carrying the yarn guide is moved up on the screwed rod by means of ratchet mechanism the effective operation of which is controlled by the yarn.

According to the invention, the screwed rod is rotatable and actuated by a ratchet

mechanism on the rising and falling carrier bar said mechanism being operated during movement of the carrier bar by a relatively fixed, preferably adjustable, cam or equivalent and rendered inoperative by a device controlled by the yarn.

In further describing the invention reference will be made to the accompanying drawings in which:—

Figure 1 is a plan of a convenient form of the improved mechanism constituting an example of the invention.

Figure 2 is a side elevation of the same.

Figure 3 is a front view of part of the mechanism.

Figure 4 is an underside view of the parts shown in Figure 5.

Figure 5 shows the ratchet device in vertical section on the line 5—5 of Figure 4.

Figure 6 is a sectional plan taken on the line 6—6 of Figure 2.

Figure 7 is an elevation, and

Figure 8 is a plan of a modified form of mechanism covered by the invention.

Figures 1 and 2 are drawn to a smaller scale than the remaining figures, and throughout the drawings like parts are designated by the same reference characters.

Referring to Figures 1 to 6, the screwed rod 1 is rotatably mounted in a bearing 2 attached to the carrier bar 3 and has fixed upon its lower end a ratchet wheel 4. A lever 5 mounted to oscillate on the lower part of the rod 1 above the ratchet wheel 4 carries a spring controlled pawl 6 which engages with the teeth of the ratchet wheel 4 as clearly shown in Figure 4. The lever 5 is actuated in one direction by a coil spring 7 and upon the carrier bar 3 descending, said lever makes contact with and is moved by the inclined edge 8 of a member 9 attached to the stationary bed or table 10 of the machine. This movement of the lever takes place against the action of the spring 7 and imparts a part rotation to the ratchet wheel 4 and screwed rod 1.

To prevent back movement of the ratchet wheel after the latter has been advanced and when, upon the carrier bar 3 rising, the lever 5 is moved in the reverse direction by its spring 7, a pawl 11 is arranged

as shown in Figure 4 and operated by a spring 11^a to engage the ratchet wheel. This pawl is attached to the lower end of a cranked rod 12 against which the spring 5 11^a bears.

The yarn guide 13 is attached to a nut device 14 which engages the threads of the rod 1 and, as the latter is intermittently rotated, moves up the same. The nut device preferably has a spring 15 (Figures 10 2 and 6) to engage the threads so that disconnection may be readily effected for moving the device up or down on the rod by hand. To prevent rotation of the nut device 15 on the rod, a projecting part 16 thereof engages and works up and down a vertical rod 17 fixed on the carrier bar 3 and disposed parallel to the screwed rod 1.

The nut device 14 also carries a pivoted 20 arm 18 having a yarn guide 19 thereon. This guide 19 when engaged by the running yarn indicated at 20 in Figures 2 and 6 is held, by the tension of the latter, in a raised position so that a pin 21 thereon 25 is clear of the beforementioned cranked rod 12. The said rod 12 is mounted at its upper and lower ends so as to be capable of turning, and the arrangement is such, that upon breakage of or an end in the running 30 yarn, or the stoppage of the winding spindle and bobbin, the guide 19 is released and falls so that its pin 21, as the arm 18 moves down, presses against the cranked rod 12 and turns same thereby disengaging the 35 pawl 11 from the ratchet wheel 4. Upon this taking place, the ratchet wheel, being uncheck against backward movement, is actuated both forward and backward by the oscillating lever 5 and therefore merely oscillates the screwed rod 1 through a small 40 and does not raise the nut device.

It is to be understood that the teeth of 45 the ratchet wheel 5 are so formed and the actuating pawl 6 is so arranged and controlled by its spring 22 that there will be sufficient engagement between the two for the wheel to be drawn back by the pawl when backward motion is permitted in the manner described. Upon the yarn being 50 restored, the guide 19 is lifted by the tension of the yarn, the spring 11^a acts upon the rod and brings the pawl 11 into engagement with the ratchet wheel 4 and the upward feed of the nut device 14 continues 55 when the carrier bar 3 rises and falls.

In the construction shown the movable 60 yarn guide 19 is actuated by gravity, but alternatively, it may be actuated by a spring. In any case, when the cranked rod 12 is turned by the action of the ratchet teeth passing the back-stop pawl 11 during the advance movement, the pin 21 drops into position to lock the said rod and prevent the back-stop pawl dropping back into 65 the teeth of the ratchet wheel.

The yarn guides 13 and 19 may be made of glass or porcelain or be rotatable or otherwise formed to reduce friction at the part engaged by the yarn. For engaging with the inclined edge 8 of the member 9 70 the oscillating lever 5 may be fitted with a roller (not shown).

In order to vary the extent of the engagement of the lever 5 with the incline 75 8 there is provided on the inside of the member 9 an upright guide 23 (Figures 1 and 2) the base 24 of which is arranged to turn on a pivot screw 25. The upright guide 23 may be advanced or retarded 80 along the inclined edge 8 by a push rod 26 which is held in position after adjustment by a screw binding device 27 attached to the bed or table 10. During part of its upward and downward travel the lever 5 rides against the adjacent side of the guide 85 23 and during the remaining part of its travel it rides on the inclined edge. Adjustment of the guide 23 in the manner described increases and decreases period of contact of the lever 5 with the inclined edge 90 and consequently the amount of oscillating movement imparted to said lever may be varied. This enables the amount of feed or rise imparted to the nut device at each 95 traverse to be varied in accordance with the requirements of the particular yarn being wound.

In Figure 1 the winding spindle is indicated at 28. The projecting part 16 of the nut device is fitted with a knot detector 29 100 of known form.

In the modified construction shown in Figures 7 and 8 the oscillating lever 5 is arranged underneath the ratchet wheel 4 on the lower end of the screwed rod 1 and 105 is actuated in both directions by the engagement of a roller 30 thereon with an inclined slotted plate 31 attached to a bracket 32 secured on the bed or table 10. As the carrier bar 3 rises and falls relatively to 110 the table 10, the roller 30 travels up and down in the slot 33. By slackening the nut 34 the inclination of the slotted plate 31 may be varied by hand thereby varying 115 the amount of oscillation imparted to the lever. With this arrangement the spring for moving the lever in one direction can be eliminated. The other parts of the mechanism are the same as already described.

What I claim then is:—

1. In a yarn winding machine of the vertical spindle type, in combination, a rising and falling carrier bar, a screwed rod rotatable thereon, a nut device moved up on said rod when the latter is rotated, a yarn guide carried by said nut device, a ratchet wheel fast on the screwed rod, a lever mounted to oscillate on the screwed rod, a pawl on said lever engaging the ratchet wheel, a fixed cam to oscillate the 120

lever during movement of the carrier bar, a pawl to prevent backward rotation of the ratchet wheel, a pivoted arm on the nut device said arm being controlled by the yarn, 5 and a connection between said arm and last mentioned pawl, whereby, upon release of the arm by the yarn the said pawl is disengaged from the ratchet wheel to stop rotation of the screwed rod.

10 2. In a yarn winding machine of the vertical spindle type, in combination, a rising and falling carrier bar, a vertical screwed rod rotatable thereon, a nut device moved up on said rod when the latter is rotated, 15 a vertical guide rod for said nut device, a yarn guide carried by said nut device, a ratchet wheel fast on the screwed rod, a lever mounted to oscillate on said rod, a pawl on said lever engaging the ratchet wheel to drive same, a stationary adjustable inclined cam with which the lever makes contact and by which it is oscillated during movement of the carrier bar, a vertical pivoted cranked rod, a pawl on the end 45 thereof adapted to prevent backward rotation of the ratchet wheel, a spring controlling said rod, and a pivoted arm on the nut device said arm being normally controlled by the yarn and upon release thereby actuating the cranked rod to disengage the last mentioned pawl from the ratchet wheel to stop rotation of the screwed rod.

20 25

ratchet wheel to stop rotation of the 30 screwed rod.

3. In a yarn winding machine of the vertical spindle type, in combination, a rising and falling carrier bar, a vertical screwed rod rotatable thereon, a nut device moved up on said rod when the latter is rotated, 35 a vertical guide rod for said nut device, a yarn guide carried by said nut device, a ratchet wheel fast on the screwed rod, a lever mounted to oscillate on said rod, a pawl on said lever engaging the ratchet 40 wheel to drive same, a stationary adjustable inclined cam with which the lever makes contact and by which it is oscillated during movement of the carrier bar, a vertical pivoted cranked rod, a pawl on the end 45 thereof adapted to prevent backward rotation of the ratchet wheel, a spring controlling said rod, and a pivoted arm on the nut device said arm being normally controlled by the yarn and upon release thereby actuating the cranked rod to disengage the last mentioned pawl from the ratchet wheel to stop rotation of the screwed rod.

In testimony whereof I have signed my name to this specification.

JOHN JAMES CANNON.
